UNITED STATES PATENT OFFICE.

OSCAR A. ROSS, OF NEW YORK, N. Y.

SYNCHRONIZED MACHINE GUN FOR AIRPLANES.

Application filed April 9, 1927. Serial No. 182,346.

This invention relates to systems for operating machine guns from air planes and comprises a modification of the invention disclosed by Patent #1,454,137, issued to the 5 applicant May 8, 1923.

At the time the patent application for the aforesaid patent was filed, namely September 14, 1918, air planes of the pursuit type were employing propellers constructed of laminated wood, and the rotative speed of such propellers was limited to 1000 to 1600 R. P. M., it also being customary to employ gearing between the engine and propeller to obtain the maximum output of said engine.

15 At the present time metal propeller blades are employed at normal speeds of approximately 2000 R. P. M., and this speed may increase as much as 3000 R. P. M. in "nose dive attacks" with engine "wide open". Obviously at these higher rotative speeds the increment of time between blade movements is very small, and whereas the rapidity of machine gun cycle has been increased from a normal of 400 to 800 shots and a maximum of 25 1200 per minute, the time interval between the "pulling of the trigger", and the passing of the bullet through the plane of movement of the propeller blades has not increased in the same proportion as the rapidity of fire.

30 As a matter of fact, at the present high rotative speeds of propellers, and after a trigger is pulled as many as 3 blades, (one and one-half revolutions) may pass a gun barrel before the bullet passes the plane of movement 35 of the propeller. It is therefore obvious that, if a gun is timed to fire just after a blade has passed at slow speed, after a predetermined increase in speed, the blades of the propeller will intercept said bullets, thereby 40 causing injury to said blades.

One of the prime objects of this invention is to furnish means to automatically vary the time of firing of machine guns, whereby the bullets will pass between the blades, irrespective of the speed at which the propeller may be revolving.

Another object is to furnish means whereby a plurality of guns may be fired sequentially at low propeller speeds, and at such 50 speeds as will permit sequential firing of two or more guns between successive blade movements.

55 Another object is to furnish gun actuating means controlled by a speed governor, whereby the energy required for said actuation will be substantially uniform, in this manner per-

mitting the governor to vary the actuating means substantially in proportion to the speed of the propeller.

Other objects and advantages will appear as the description of the invention progresses, and the novel features of the invention will be pointed out in the appended claims.

This invention consists in the novel construction and arrangement of parts herein-after described, delineated in the accompanying drawings, and particularly pointed out in that portion of this instrument wherein patentable novelty is claimed for certain and peculiar features of the system, it being understood that, within the scope of what hereinafter thus is claimed, divers changes in the form, proportions, size and minor details of the structure may be made without departing from the spirit of, or sacrificing any of the details of the invention.

In describing the invention in detail, reference is had to the accompanying drawings, wherein I have illustrated embodiments of my invention, and, wherein like characters of reference, designate corresponding parts throughout the several views, and, in which:—Fig. 1, is a diagrammatic view of an air plane motor, four machine guns and control apparatus therefore, and is taken in part on line A—A of Fig. 2, and, Fig. 2, is a diagrammatic view of the governor controlled contacting mechanism, and is taken on line B—B of Fig. 1, and, Fig. 3, is a chart of the contact drum periphery shown in Figs. 1, and 2, and, Fig. 4, is a diagrammatic view of relative location and operation of guns and propeller, taken on line E—E of Fig. 1, and, Fig. 5 is a similar view, and Fig. 6 is a diagrammatic view of a mechanical control apparatus for firing the guns, and is taken on line C—C of Fig. 7 and Fig. 7 is also a diagrammatic view of the same apparatus, and is taken on line D—D of Fig. 6.

Referring to Figs. 1, 2, and 3, to motor 1, having a two-blade propeller 2, are suitably mounted machine guns, R, S, T and U, adapted to be fired by electro-magnets R¹, S¹, T¹ and U¹.

Preferably secured to half time shaft 15 of motor 1, is governor 6, secured by pin 7, the controlling disk 8, of which is secured to contact drum 9, slidably mounted on shaft 15, imbedded in the periphery of which is contact strip 10 adapted to contact with brushes R⁴, R⁵, S⁴, S⁵; T⁴, T⁵; and U⁴, U⁵; said strip receiving energy through conductor 11, con-

nected to commutator 12, contacting with brush 13 communicating to the manually operated trigger 31.

Referring to Figs. 6, and 7, machine guns R, S, T and U have "triggers" R¹⁶, S¹⁶, T¹⁶ and U¹⁶ adapted to be actuated by cams R¹⁷, S¹⁷, T¹⁷ and U¹⁷, secured to drum 18, one end of which is mounted on bearing 19 adapted to restrain axial movement thereof, and 10 the other guided by screw member 20, slideable on shaft 15 and actuated by governor 6.

The operation of the system is as follow:—

Referring to Figs. 1, 2, 3, 4, and 5, when motor 1 is at rest, the governor 6, assumes the 15 dotted position shown, the drum 9 impinges on collar 21, and the brushes R⁴, R⁵, to U⁴, U⁵, inclusive, are bearing along line X—X on said drum as shown in Fig. 3. If the motor 1 is now slowly rotated, the location of contact 20 strip 10 is such, that, just after blade 2^a has passed gun R and the manually operated trigger 31 is depressed, said gun will be fired by the energizing of the following circuit.

R gun circuit, from positive energy to 25 manually operated trigger 31, brush 12, commutator 13, conductor 11, contact strip 10, brush R⁴, wires R²⁵ and R²⁶, to the trigger operating magnet R³, returning to negative energy. As magnet R³ is actuated, it closes 30 contacts R²⁷ and R²⁸, establishing a partial circuit to gun S, as follows: from positive energy as before named to contact strip 10, thence (assuming brush R⁵ is in contact with said strip) to brush R⁵, wire R²⁹, contacts 35 R²⁸ and R²⁷, wires R³⁰ and S³¹, to magnet S³, returning to negative energy. If drum 9 is stationary with brushes R⁴ and R⁵ in contact with strip 10, guns R and S will continue to fire in sequential order, gun R causing 40 gun S to be fired by the operation of the mechanism which fires gun R. If the motor 1 is now accelerated to a speed whereby the time interval between blade movement is insufficient to safely fire gun S in sequential 45 order by gun R, the drum 9 will be revolving at a sufficient speed, whereby the contact strip 10 will leave brush R⁵ before the contacts R²⁷ and R²⁸ are closed, in this manner preventing the operation of gun S, as contacts R²⁷ and 50 R²⁸ are closed.

As drum 9 is slowly rotated in the direction of the arrow Y, contact strip 10 will contact with brush S⁴, and the circuit to gun S will be established in a similar manner as described for gun R. Further rotation of drum 55 9 causes guns T and U to be fired in sequential order, and still further movement of the drum again causes firing of gun R, this sequential order of firing being fully described in Patent No. 1,454,137.

Assume now the motor 1 has accelerated to a speed of 3000 R. P. M., due to a "nose dive attack". The governor 6, and drum 9 will assume the location shown by Figs. 1 and 2, and 60 the firing of the guns as R, S, T and U will

be advanced substantially three-blade movements, as will be more fully hereinafter described. For the purpose of expeditious description, the following factors will be assumed:

Normal engine speed approximately 2000 R. P. M. or 4000 blade movements per minute, or 1/67 second per blade movement, or 67 per second.

Maximum engine speed approximately 75 3000 R. P. M. or 6000 blade movement per minute, or 100 per second, or 1/100 second per blade movement.

Normal gun fire approximately 1000 shots per minute, or 16 per second, or, 1/16 second per shot. Time interval of gun cycle including "pulling of trigger" up to passing of bullet through plane of movement of propeller blades, to equal 1/3 of gun cycle, or, 1/50 second.

For the purpose of clearer illustration, the time interval represented by the width of the blade is assumed to be nil, the blade being further assumed to be a radial line of nil dimension.

From the foregoing computations, it will be obvious that, if gun R is ordinarily fired just after the blade 2^a (Fig. 5) passes the gun barrel, and the motor 1 is operating at a speed of 2000 R. P. M., the blade 2^b will also have 90 passed said barrel before the bullet has reached the plane of movement of the propeller blades. If the engine speed is reduced to approximately 1500 R. P. M., the blade 2^b will intercept the bullet and injury 100 to said blade may result.

If the motor 1 is operated at 3000 R. P. M. and gun R is ordinarily fired just after blade 2^a has passed the gun barrel, not only blade 2^b, but in addition blade 2^a will again pass the 105 barrel before the bullet has reached the plane of movement of the propeller. It is also obvious that blade 2^a has just cleared the line of bullet travel and that a slight reduction of speed will cause said blade 2^a to intercept 110 the bullet, resulting in probable injury to said blade.

With the applicant's novel system of firing synchronized machine guns sequentially, such interference of bullets and blades is 115 eliminated in the following manner:

When the motor 1 is at rest or is revolved very slowly, the guns R, S, T and U are fired just after the blade, as 2^a, has passed the gun R, of Fig. 5; however, as the engine speed is increased the governor 6 moves drum 9 axially on shaft 15, and away from stop collar 21, in this manner causing contact strip 10 to make earlier contact with brushes as R⁴, R⁵, S⁴, S⁵, T⁴, T⁵; U⁴, U⁵, whereby the firing period of said gun is advanced with respect to the location of the propeller blades; as a matter of fact it will be obvious that at certain increased speeds, as the motor 1 accelerates from zero revolutions, the guns, as R to U, 125 130

inclusive, have their "triggers pulled" when the blades are directly opposite their gun barrels.

In this improved system for firing synchronized machine guns sequentially, the timing of firing of guns as R to U inclusive at high rotative propeller speeds, as for example 3000 R. P. M. is such, that, the bullet passes the plane of movement slightly before the equa-distant line of the blade opening passes the line of the gun barrel, see Fig. 4, the included angle W, representing the factor of safety prior to intersection of the plane of movement of propeller blades, and the included angle L, the factor of safety, subsequent to said intersection, the latter angle being somewhat larger to compensate for variable ammunition characteristics.

Referring to Figs. 6 and 7, at nil speed of motor 1, the governor 6 restrains screw 20 to enter drum 18, thereby causing said drum to be rotated counter clockwise, (see Fig. 7) and the guns R to U inclusive will be sequentially fired just after a blade, as 2^a or 2^b, has passed a gun barrel. As the speed of motor 1 increases the governor 6 will restrain screw 20 to withdraw from the drum, in this manner causing a clockwise movement of the drum, whereby the period of sequential firing will be advanced with respect to the propeller line of action and the ultimate result of gun action will be the same as described in connection with Figs. 1, 2, 3, 4, and 5.

It is to be noted that the cams as R¹⁷ to U¹⁷ inclusive, have uniformly increasing contours. Also that the pressure of one "trigger" as R¹⁶, is released just as another, T¹⁷, begins to be depressed, in this manner producing a uniform counter-torque to be overcome by the torque exerted by governor 6 on screw 20, for control of advancing and retarding movement of drum 18.

Figure 3 indicates the preferable advancement of gun fire, with respect to propeller movement from 0 to 3000 R. P. M. of motor, as 1.

It will be also noted from Figs. 1 and 3, that the included angle between brushes R⁴ and S⁴ is slightly greater than 90 degrees, and that this is also true of brushes S⁴ to T⁴ and T⁴ to U⁴. This increase is for the purpose of compensating for the circumferential displacement of the gun barrels, with respect to the propeller movement, as shown in Figs. 4 and 5. However, as the interval of blade opening is smaller as gun R is sequentially fired after gun U, the included angle between brushes U⁴ and R⁴ is less than 90 degrees, and for the same reason cam R¹⁷ is shorter than cams S¹⁷, T¹⁷ and U¹⁷.

If desired the cams R¹⁷ to U¹⁷ inclusive may be replaced by eccentrics for operating the gun "triggers" and such an arrangement will avoid the necessity of spring return of said "triggers", in this manner still further re-

ducing the counter-torque to be overcome by the torque produced by the governor 6.

If desired the brushes, as R⁴, R⁵; S⁴, S⁵; T⁴, T⁵; U⁴, U⁵; and contact drum 9, may be substituted by eight eccentrically operated levers four of which are arranged to continuously operate the "triggers" of guns as R, S, T and U, replacing the magnets R⁴, S⁴, T⁴ and U⁴, and the other four arranged to operate the "triggers" sequentially with the first named four eccentrics, the governor 6, in addition to advancing the eccentric motion, also acting, at a predetermined increase of speed, to annul the effect of the last named four eccentrics to operate the "triggers" of guns as R, S, T and U.

What I claim is:—

1. In combination with a plurality of machine guns synchronized to fire between the blades of an air plane propeller, means for driving the propeller, means controlled by the driving means for firing the guns, in sequential order, a centrifuge driven by the propeller driving means, and means controlled by the centrifuge for varying the moment of fire of the sequential firing means with respect to the blade location, whereby the bullets of the gun are restrained to pass between the blades at the plane of movement of the blades upon operation of the sequential firing means.

2. In combination with a plurality of machine guns arranged to fire sequentially between the blades of an air plane propeller, means for driving the propeller, means actuated by the driving means for firing the guns in sequential order, a centrifuge driven by the propeller driving means, and means controlled by the centrifuge for varying the moment of fire of the firing means with respect to the blade location, whereby the bullets from the guns are restrained to pass between said blades at the plane of movement of the blades upon operation of the firing means.

3. In combination with a plurality of machine guns synchronized to fire between the blades of an air plane propeller, means for driving the propeller, means actuated by the propeller driving means for firing the guns in synchronism with the propeller blades, means actuated by each gun for firing another gun, and means for annulling said last named means upon a predetermined increase of speed of the propeller driving means.

4. In combination with a plurality of machine guns synchronized to fire sequentially between the blades of an air plane propeller, means for driving the propeller, means actuated by the propeller driving means for firing the guns sequentially and in synchronism with the propeller blades, means actuated by each gun for firing another gun, and means for annulling said last named means upon a predetermined increase of speed of the propeller driving means.

5. In combination with a machine gun synchronized to fire between the blades of an air-plane propeller, of means for driving the propeller, means for firing the gun, a governor arranged to be rotated by the propeller driving means, and means controlled by the governor for rendering the firing means effective to fire the gun at one range of speed of rotation of the propeller and ineffective to 10 so fire at another range of speed thereof.
6. In combination with a plurality of machine guns synchronized to fire between the blades of an air-plane propeller, of means for driving the propeller, means for firing the 15 guns in sequential order, a governor arranged to be rotated by the propeller driving means, and means controlled by the governor for rendering the firing means effective to fire the guns sequentially at one range of speed of the 20 propeller and ineffective to so fire at another range of speed thereof.
7. In combination with a plurality of machine guns synchronized to fire between the blades of an air-plane propeller, of means for 25 driving the propeller, a governor rotated by the propeller driving means, means controlled by the governor for initially firing the guns, means controlled by the initial firing means for secondarily firing the guns, and means 30 also controlled by the governor for rendering the secondary firing means effective to fire the guns at one range of speed of the propeller and ineffective to so fire the guns during another range of speed thereof.
8. In combination with a machine gun synchronized to fire between the blades of an air-plane propeller, of means for driving the propeller, a governor rotated by the propeller driving means, an electro-magnet arranged to 35 fire the gun when energized, an electric circuit for supplying energy thereto, means controlled by the governor for supplying energy 40 to the circuit at fixed intervals and simultaneously varying the cycle of intervals in proportion to the speed of the propeller whereby 45 the projectiles for the guns will be restrained to pass between the blades of the propeller.
9. In combination with a plurality of machine guns synchronized to fire between the blades of an air-plane propeller, of means for 50 driving the propeller, a governor rotated by the propeller driving means, an electro-magnet for each gun arranged to fire the ammunition therein when energized, an electric circuit for each electro-magnet arranged to 55 supply energy thereto, means controlled by the electro-magnet for firing another gun, and means controlled by the governor for supplying energy to the circuits whereby at one range of speed of the propeller a plurality 60 of guns will be fired sequentially between each blade movement thereof and at another range of speed only one gun will be so fired.
10. In combination with a plurality of machine guns synchronized to fire between the 65 blades of an air-plane propeller, of means for driving the propeller, means controlled by the driving means for initially firing each gun in synchronism with the propeller blades, and means controlled by the initial firing 70 means for firing another gun whereby a plurality of guns will be fired in sequential order.
11. In combination with a machine gun synchronized to fire between the blades of an air-plane propeller, of means for driving the 75 propeller, means for firing the gun, means controlled by the propeller driving means for rendering the firing means effective to fire the gun at one range of speed thereof and ineffective to so fire at another range of speed. 80
